LAMINATED LINE RISER

Ernest A. Elliott, Detroit, and John W. Kane, Pontiac, Mich., assignors to The Detroit Edison Company, Detroit, Mich., a corporation of New York

Filed Jan. 23, 1967, Ser. No. 5,529

Term of patent 14 years

Int. Cl. D13—03

U.S. Cl. D26—12

FIGURE 1 is a perspective view of the laminated line riser.

FIGURE 2 is an elevational view of the riser, taken from one side thereof.

FIGURE 3 is an elevational view of the riser, taken from the position at 90 degrees to FIGURE 2.

The broken line in FIGURE 1 indicates conventional ground surface.

We claim:

The ornamental design for a laminated line riser, substantially as shown and described.
